To all whom it may concern:

Be it known that I, Theodore Ball, a citizen of the United States, residing in the city of New York, county of New York, and State of New York, have invented a new, original, and ornamental Design for a Hand Bag or Similar Article, of which the following is a specification, reference being had to the accompanying drawing, forming part thereof.

Figure 1 is a perspective view of a bag in open position and embodying my new design, the main portion of the bag being shown in dotted lines.

Figure 2 is a similar view showing the bag in closed position.

The dominant feature of the present design resides in the ornamental effect produced by the frame attached to the side of the hand bag, said frame having a group of ornamental figures each of which is suspended therefrom.

I claim:

The ornamental design for a hand bag or similar article as shown, and described.
